GASEOUS DISCHARGE DEVICE

Thomas A. Vanderslice, Schenectady, N.Y., assignor to General Electric Company, a corporation of New York

Application September 25, 1958, Serial No. 763,292

7 Claims. (Cl. 313—193)

The present invention relates to improved gaseous discharge devices and, more particularly, to improved anode structures therefor.

In gaseous rectifier devices, such as thyratrons and the like, one serious cause of tube failure after a substantial period of operation is the occurrence of gaseous "clean-up" whereby the gas pressure within the device gradually drops to a value at which a gaseous discharge may not be sustained between the anode and cathode thereof.

A further disadvantageous aspect of the "clean-up" phenomenon is the fact that, as pressure decreases, the operating parameters of the device, for example, breakdown potential and operating potential difference, are subject to change. This change may render the device useless as a control or regulatory device long before actual failure occurs.

Accordingly, one object of the present invention is to provide gaseous discharge devices having improved and longer lifetime characteristics.

Another object of the present invention is to provide gaseous discharge devices which are capable of maintaining a constant operating pressure over an extended period of time.

Still another object of the present invention is to provide improved anode structures for gaseous discharge devices.

Briefly stated, in accord with one feature of my invention, I provide an improved long-lifetime gaseous discharge device suitable for use as a rectifier or regulator of alternating electric currents and including a cathode and a closely-disposed hollow anode wherein the aperture into the anode cavity is smaller than the inside dimensions of the anode cavity. In accord with another feature of the invention, a control electrode is disposed between anode and cathode to form a triode gaseous discharge device of the thyratron type. The anode structure utilized insures substantially uniform current density over the anode surface utilized, and the hollow, partially-foreclosed anode surface facilitates control and confinement of metallic particles sputtered from the anode by positive ion bombardment during the inverse alternation of an applied alternating voltage sought to be regulated or rectified.

The novel features believed characteristic of the invention are set forth in the appended claims. The invention itself, however, together with further objects and advantages thereof may best be understood by reference to the following description taken in connection with the attached drawing in which:

Fig. 1 illustrates a gaseous three-electrode discharge device constructed in accord with one feature of the present invention.

Fig. 2 represents an alternative embodiment of the invention utilizing the disc-seal construction for gaseous discharge devices.

Fig. 3 represents a two-electrode gaseous discharge device constructed in accordance with another feature of the present invention, and

Fig. 4 represents an alternative electrode structure which may be utilized in any of the embodiments of Figs. 1, 2 and 3.

In Fig. 1, a triode gaseous rectifier or control device of, for example, the thyratron type, constructed in accord with the present invention includes an evacuable vitreous envelope which may, for example, be of Pyrex glass having re-entrant portions 2 and 3 at opposite ends

2

thereof. An electron emissive cathode 4 is supported from re-entrant portion 2 by cathode lead 5 and cathode support 6. A cathode heater 7 may be supplied and, if present, is utilized to heat cathode 4 to thermionic emission temperatures by virtue of its location within the cup of cathode 4. Heater 7 is supported by and electrically connected to a suitable filament supply by support and lead-in wires 8 which pass through re-entrant portion 2 of envelope 1. A hollow anode 9 is composed of a hollow metallic shell in the form of a hollow oblate spheroidal body, truncated along a line substantially perpendicular to the polar axis thereof to form aperture 10. The interior of anode 9 defines anode cavity 12. A control grid or electrode 11 is interposed between cathode 4 and hollow anode 9 and serves to control the passage of electric current therebetween. The interior of envelope 1 is filled with a noble gas as, for example, argon, at a pressure of the order of 5-10 microns of mercury. Cathode electrode 4 is composed (if thermionically operated) of a low-work function material as, for example tungsten or thoriated tungsten. The interior surface 13 of anode 9 bordering upon anode cavity 12 is the active anode surface and is conveniently formed of a material which is difficultly sputtered under positive ion bombardment such as niobium or tungsten. The exterior of anode shell 9 is conveniently, but not necessarily coated with a non-conducting layer 14 to prevent the footpoint of a glow discharge being established upon the anode exterior rather upon the interior thereof. An alternating voltage to be rectified is connected across anode and cathode electrodes. Current flows therebetween when the anode is sufficiently positive to overcome the negative bias of control electrode 11.

In the operation of devices similar to that illustrated in Fig. 1, but possessing a conventional planar or cupped shaped anode, tube life and tube reliability and stability have, heretofore, been seriously affected by a constant and progressive lowering of the pressure of the inert gases with which the device is charged. I have determined that this lowering of gas pressure or gas "clean-up" is the result of the formation, upon the interior walls of the tube envelope, of a thin layer of metal which is sputtered from the anode electrode by positive ion bombardment during the inverse cycle of an alternating voltage across which device is connected and which the device is utilized to control or rectify. Thus, in operation, a glow discharge is established between cathode and the anode when the positive potential applied to the anode is sufficient to overcome the negative field established by a potential applied to the control electrode. The glow discharge continues as long as the anode remains positive with respect to the cathode. When, however, the alternating voltage applied between cathode and anode reverses polarity and the anode becomes negative, a glow discharge is not re-initiated because substantial cold emission does not occur from the anode. At that time, however, there are a large number of ionized gas molecules present in the space between the anode and cathode. These positive inert gas ions are then accelerated into the anode and strike the anode with energies sufficient to cause the ejection of particles of anode material therefrom. These particles migrate to the tube walls where they form a sink for the deposition of positive gas ions which are subsequently covered up by further sputtered metallic particles. Thus, over a long period of time a number of gaseous ions are collected in materials sputtered to the tube walls from the anode and the gas pressure falls, eventually causing tube failure.

A further disadvantage, in triode devices as, for example those illustrated in Fig. 1 of the drawing, is that, with a planar anode, the control electrode casts a shadow upon the anode and portions of the anode which are

shielded from the cathode by a closely spaced control electrode are not subjected to the same current density as the portions of the anode not so shielded. Under these circumstances, those portions of the anode which are subjected to a high current density are eroded by constant positive ion bombardment during the inverse cycle, whereas the portions of the anode which are shadowed by the control electrode or grid are not eroded but are, on the contrary, built-up by the deposition thereupon of sputtered metallic particles which are removed from the remaining portions of the anode by positive ion bombardment. These portions of the anode likewise serve as a sink for the reception of gas ions and the entrapment thereof by sputtered metal. This phenomenon also contributes to the cleaning up of gas within the tubes, decreasing of gas pressure, in the eventual failure of the tube.

The device of Fig. 1, on the other hand, prevents the foregoing cleaning up actions by virtue of two separate but interrelated characteristics of anode 9. Initially, it has been found that the non-planar anode surface 13 results in a substantially uniform current density over all portions thereof irrespective of the presence of control electrode 11. This completely eliminates, from triode devices, any effect of "grid shadow" which causes the creation of small gas ion sinks on the anode surface itself.

Additionally, and of greater importance, is the fact that the restricted entrance of orifice 11 into anode cavity 12 very greatly reduces the probability that metallic particles sputtered from one portion of the interior surface 13 of anode 9 will possibly be able to migrate to the interior of envelope 1 to cause the formation of a sink for gaseous ions which may later be covered up and removed from the device by subsequently sputtered metallic particles, lowering the pressure thereof. In the anode configuration utilized in the device of Fig. 1 and in equivalent anode structures, most anode material sputtered from the interior surface 13 of hollow anode 9 by positive ion bombardment during the inverse cycle of an applied alternating voltage is collected at another portion of the anode surface due to the fact that the solid angle subtended from any given spot on the anode surface 13 by orifice 11 is a relatively small fraction of the total solid angle. In the operation of the device of Fig. 1, any metallic particles sputtered from the interior surface 13 of anode 9 generally are collected by another portion of the same surface and very little of the anode material is allowed to escape from the interior of anode cavity 12. No gaseous ions are entrapped at the anode because these deposited metallic particles are continuously re-sputtered. The "clean-up" of inert gas is therefore substantially prevented and the gas pressure within the discharge device remains substantially constant over the entire tube life which is determined, then, by factors other than by gas "clean-up". In this embodiment of the invention gas "clean-up" is further prevented by the utilization of a difficultly sputtered material, such as niobium or tungsten, as the interior surface 13 of anode electrode 9.

In Fig. 2 of the drawing there is illustrated a disc-seal analogue of the device of Fig. 1.

In Fig. 2, cathode 20, control electrode 21 and anode block 22 having a truncated oblate spheroidal active anode surface 23 on the interior thereof, access to which is gained through aperture 24, and defining an anode cavity 25 are analogous to cathode, control electrode and anode of the device of Fig. 1. Additionally, as is consistent with the disc-seal technique of fabricating electric discharge devices, an annular flange portion 26 connected with cathode 20 mechanically supports cathode 20 and facilitates electrical contact thereto. Likewise, an annular ring 27 is connected with, and supports, control electrode 21. The outside diameter of both of these members is substantially the same as the exterior diameter of anode block 22. This facilitates the assembly of

the device in conventional disc-seal fashion whereby alternate metallic members 22, 26 and 27 are separated by ceramic members of a like exterior dimension to form an hermetically sealed envelope. To complete the structure, a heater filament 28 may be enclosed within the cup of cathode 20. One end of heater filament 28 is connected to metallic end member 29 and the other lead is connected to cathode 20. To complete the evacuable envelope of the discharge device illustrated in Fig. 2, anode 22 is electrically insulated from, and hermetically sealed to, control electrode support member 27 by a suitably counterbored and recessed ceramic member 30. Member 27 is electrically insulated from, and hermetically sealed to, annular member 26 by a suitable annular ceramic member 31, properly counterbored and recessed. Member 29 is likewise electrically insulated from, but hermetically sealed to, member 26 by annular member 32.

The device of Fig. 2 may be assembled and sealed in an inert atmosphere by the process disclosed and claimed in the copending application of James M. Lafferty, S.N. 690,849, filed Oct. 17, 1957, and assigned to the same assignee as the present invention. The operating characteristics of the device of Fig. 2 are identical with those of the devices of Fig. 1 and the advantages gained therefrom over triode rectifier or regulating devices is identical thereto, the main difference being that this device incorporates only metallic and ceramic members and has all the advantages of ceramic and metal disk-seal discharge devices.

In Fig. 3 of the drawing there is illustrated a two-element gaseous electric discharge device constructed in accord with the present invention. The device of Fig. 3 may be a voltage regulator or voltage reference tube utilized to maintain a constant voltage across a network or alternatively may be a simple rectifier device utilized to rectify an alternating voltage.

The device of Fig. 3 is similar to that of Fig. 2 but is a two electrode device, including a cathode 35 and an anode 36 having an anode cavity 37 therein and an active anode surface 38. Cathode 35 is supported by annular member 39 which is electrically insulated from, but hermetically sealed to, anode block 36 by a properly counterbored and grooved annular insulating member 40. Cathode 35 may be raised to thermionic emission temperatures by a heater filament 41, one end of which is connected to cathode 35, and the other end of which is connected to end member 42 which is electrically insulated from and hermetically sealed to, annular cathode support 39 by means of annular ceramic member 43.

In the operation of the device of Fig. 3 the space between the cathode and anode surface is filled with a suitable noble gas as, for example argon, at a suitable pressure as, for example, from 5-10 microns of mercury pressure and, when anode surface 38 is maintained positive with respect to cathode 35, a glow discharge is initiated therebetween. While the discharge exists between anode and cathode, the voltage difference therebetween is limited to a very low voltage as, for example, 8 volts. When, however, the inverse cycle of the applied alternating voltage occurs, and anode 38 becomes negative with respect to cathode 35, no discharge exists and the line voltage is applied between anode and cathode. This causes ionized inert gas molecules remaining from the previously existing glow discharge to be driven with high velocity into anode surface 38, causing the sputtering of metallic particles therefrom. In accord with the present invention these metallic particles are, with a high probability, redeposited upon other portions of anode surface 38 because of the small aperture in the hollow anode block 36 as compared with the entire area of anode surface 38. This prevents the accumulation of sputtered anode material upon the interior walls of the device which would provide a sink for the accumulation of noble gas ions and a resultant lowering the gaseous pressure with the

device. Additionally, the hollow anode, with a restricted entrance thereto reduces to a low value the probability that ionized gaseous molecules will migrate to the cold walls of the tube and possibly damage the ceramic or glass-to-metal seals. This advantage exists in all embodiments of the invention.

In Fig. 4 of the invention there is shown, schematically, an alternative anode structure which may be applied to any of the embodiments of the invention illustrated in Figs. 1, 2 and 3. In Fig. 4 the anode structure, rather than being an oblate spheroid, as are the anode cavities in the devices of Figs. 1, 2 and 3 is, rather, a hollow cylindrical body 44 with an inwardly depending flange or cap at the end thereof. Although this structure does not have the ideal characteristics of the anodes illustrated in Figs. 1, 2 and 3 it may be fabricated with greater ease and, therefore, is less expensive and more easily manufactured. The anode of the Fig. 4 may readily comprise a metallic disc 45 to which there is connected an annular member 46 which is capped with annulus 47, all connections being made by spot welding, brazing, soldering or other well known techniques. The material from which anode 44 of Fig. 4 is constructed may be any suitable material as mentioned hereinbefore which is difficult to sputter under positive ion bombardment. In all embodiments of the invention it is desirable that the ratio of aperture diameter to anode cavity diameter be $\frac{1}{2}$ or less to secure the full benefits of the invention.

It should be noted that the present invention is related only to gaseous discharge tubes wherein a finite amount of a gas such as the inert and noble gases, for example, nitrogen, helium, neon, argon, krypton, xenon and radon are utilized as the sole ionizable medium for the conduction of electric current between the cathode and anode thereof. This invention is based upon my discovery of the mechanism of gas "clean-up" in such tubes and therefore is entirely unrelated to other types of discharge devices, such as tubes operating in vacuo, wherein a finite gas pressure is not necessary, or pool-type discharge devices, such as mercury vapor tubes of the thyratron or an ignitron type, wherein a continuous vapor replenishing reservoir is provided as, for example, by a pool of mercury in the vicinity of the cathode. Obviously, since there is a continuously replenishable supply of mercury vapor in such devices, a provision of an anode such as is disclosed in the present application would have little or no added advantage.

While the invention has set forth hereinbefore with respect to certain embodiments thereof, many modifications and changes will immediately occur to those skilled in the art. Accordingly, by the appended claims I intend to cover all such modifications and changes as fall within the true spirit and scope of the invention.

What I claim as new and desire to secure by Letters Patent of the United States is:

1. A gaseous electric discharge device comprising an evacuable envelope having therein a cathode electrode and a hollow anode electrode having an aperture therein, the largest dimension of said aperture being less than the interior dimension of said hollow anode by a factor of no greater than $\frac{1}{2}$ measured in a plane substantially parallel with the plane defined by said aperture, said cathode and said anode being closely juxtaposed so as to sustain a glow discharge therebetween; and a pressure of gas sufficient to sustain a discharge constituting ionized gas particles within said envelope.

2. A gaseous electric discharge device comprising an evacuable envelope containing therein a cathode and an anode electrode each of which has an active surface adapted to serve as the terminal point of an ionized gaseous discharge, said anode surface being the surface of a partially enclosed cavity the entrance aperture of which is in a plane substantially parallel to the plane of the active surface of said cathode and which is smaller in dimension than the dimension of said cavity by a factor

no greater than $\frac{1}{2}$ measured substantially parallel with the plane of said aperture, and a pressure of gas sufficient to sustain a discharge constituting ionized gas particles within said envelope.

- 5 3. A gaseous electric discharge device comprising an evacuable envelope having therein a cathode electrode and a hollow anode electrode, the active surface of which is the interior surface of a truncated curved cavity within said anode, said cavity being terminated in an aperture 10 in a plane substantially parallel with the active surface of said cathode, the dimension of said aperture being less than the dimension of said cavity substantially parallel with said plane; and a pressure of gas sufficient to sustain a discharge constituting ionized gas particles within said envelope.
- 15 4. A gaseous electric discharge device comprising an evacuable envelope having therein a cathode electrode and an anode electrode closely disposed to one another and having active surfaces adapted to form the terminal 20 points of a gaseous electric discharge, said active anode surface being the interior of a hollow cylindrical body having a completely closed end at a point remote from said cathode and an inwardly depending annular flanged end at a point closely disposed to said cathode, the interior dimension of said flanged member being no greater 25 than $\frac{1}{2}$ the interior diameter of said cylindrical body; and a pressure of gas sufficient to sustain a discharge constituting ionized gas particles within said envelope.

- 30 5. A gaseous electric discharge device comprising an evacuable envelope having therein a cathode electrode and an anode electrode closely disposed to one another and having active surfaces adapted to form the terminal 35 points of a gaseous electric discharge, said anode surface being the inner surface of a truncated oblate spheroidal cavity in said anode, the entrance aperture to said cavity having a diameter substantially parallel to said cathode emissive surface which is less than the diameter of the spheroidal cavity substantially parallel therewith; and a pressure of a gas sufficient to sustain a discharge constituting ionized gas particles within said envelope.

- 40 6. A gaseous electric discharge device comprising an evacuable envelope having therein a cathode electrode and an anode electrode closely disposed to one another and having active surfaces adapted to form the terminal 45 points of a gaseous electric discharge, said active anode surface being the interior of a hollow cylindrical body having a completely closed end at a point remote from said cathode and an inwardly depending annular flanged end at a point closely disposed to said cathode, the interior dimension of said flanged member being no greater than $\frac{1}{2}$ the interior diameter of said cylindrical body; a control electrode interposed between said cathode and said anode and a pressure of gas sufficient to sustain a discharge constituting ionized gas particles within said envelope.

- 50 7. A gaseous electric discharge device comprising an evacuable envelope having therein a cathode electrode and an anode electrode, closely disposed to one another and having active surfaces adapted to form the terminal 55 points of a gaseous electric discharge, said active anode surface being the inner surface of a truncated oblate spheroidal cavity in said anode, the entrance aperture to said cavity having a diameter substantially parallel to said cathode active surface which is less than the diameter of the spheroidal cavity substantially parallel therewith; a control electrode interposed between said cathode and said anode and a pressure of gas sufficient to sustain a discharge constituting ionized gas particles within said envelope.
